(57) **CLAIM**

The ornamental design for a product delivery door for vending machine, as shown and described.

DESCRIPTION

FIG. 1 is a front perspective view of the first embodiment of a product delivery door for vending machine, showing my new design;

FIG. 2 is a front perspective view of the product delivery door for vending machine of FIG. 1 shown in a partial open position;

FIG. 3 is a front perspective view of the product delivery door for vending machine of FIG. 1 shown in a half open position;

FIG. 4 is a front perspective view of the product delivery door for vending machine of FIG. 1 shown in a fully open position;

FIG. 5 is a front view of FIG. 1;

FIG. 6 is a right side view of FIG. 1;

FIG. 7 is a left side view of FIG. 1;

FIG. 8 is a rear view of FIG. 1;

FIG. 9 is a top plan view of FIG. 1;

FIG. 10 is a bottom plan view of FIG. 1;

FIG. 11 is a front perspective view of the second embodiment of a product delivery door for vending machine;

FIG. 12 is a front perspective view of the product delivery door for vending machine of FIG. 11 shown in a partial open position;

FIG. 13 is a front perspective view of the product delivery door for vending machine of FIG. 11 shown in a half open position;

FIG. 14 is a front perspective view of the product delivery door for vending machine of FIG. 11 shown in a fully open position;

FIG. 15 is a front view of FIG. 11;

FIG. 16 is a right side view of FIG. 11;

FIG. 17 is a left side view of FIG. 11;

FIG. 18 is a rear view of FIG. 11;

FIG. 19 is a top plan view of FIG. 11;

FIG. 20 is a bottom plan view of FIG. 11;

(Continued)

FIG. 21 is a front perspective view of the third embodiment of a product delivery door for vending machine;
 FIG. 22 is a front perspective view of the product delivery door for vending machine of FIG. 21 shown in a partial open position;
 FIG. 23 is a front perspective view of the product delivery door for vending machine of FIG. 21 shown in a half open position;
 FIG. 24 is a front perspective view of the product delivery door for vending machine of FIG. 21 shown in a fully open position;
 FIG. 25 is a front view of FIG. 21;
 FIG. 26 is a right side view of FIG. 21;
 FIG. 27 is a left side view of FIG. 21;
 FIG. 28 is a rear view of FIG. 21;
 FIG. 29 is a top plan view of FIG. 21; and,
 FIG. 30 is a bottom plan view of FIG. 21.
 The broken line shown is for the purpose of illustrating portions of the vending machine that form no part of the claimed design.
